SEAT FOR PACKAGE BINDING STRANDS

Richard A. Walker, St. Joseph, Mo.

Application May 26, 1941, Serial No. 395,239

1 Claim. (Cl. 206—60)

My invention relates to improvements in seats for package binding strands.

It is of a type used to prevent binding strands, such as wires, cords, cables or ropes from indenting or cutting into relatively yielding packages, such as paper cartons or pasteboard boxes, which the strands embrace, the seat having means for preventing its shifting during transportation.

The object of my invention is to provide a novel seat of the kind described, which has not sharp points or corners which are liable to cut into the package, or cut or injure the fingers of the person who is binding the package to which the strands are being applied. My invention achieves this object by the provision of a novel seat having curvilinear edges.

A further object of my invention is the provision of a novel seat of the kind described which is cheap to make, strong, durable, not likely to be accidentally bent out of proper operative shape, which is light, may be easily nested for storage in compact form, and which is efficient in its operation.

The novel features of my invention are hereinafter fully described and claimed.

In the accompanying drawing which illustrates the preferred embodiment of my invention,

Fig. 1 is a perspective view of a package to which strand seats of my invention are applied in operative positions.

Fig. 2 is a plan view of a disk from which one of my improved strand seats is to be formed.

Fig. 3 is a plan view of the disk after the ridges have been formed thereon.

Fig. 4 is a side view of the completed seat, looking at the two diverging portions.

Fig. 5 is a side view of the seat with one side shown vertically and the other horizontally.

Fig. 6 is an end view of the strand seat.

Similar characters of reference designate similar parts in the different views.

My improved strand seat is made of thin material, preferably sheet steel or brass, consisting primarily of a sheet metal disk 1, Fig. 2, across the middle portion of which are formed two parallel ridges 2, which form between them a di-
ametrical groove 3, Fig. 3.

The disk thus formed is then bent at right angles to the groove 3 to form the completed strand seat, shown in Figs. 1, 4, 5 and 6, having two portions 4 which are alike, in the form shown in the drawing. The portions 4, in the form shown are bent at an angle to each other approximately that between two meeting sides, as 5 and 6, Fig. 1, which sides of a package 7, said portions 4 are intended to respectively embrace.

If the package 7 is rectangular, the portions 4, are, preferably, bent at an angle to each other slightly less than a right angle, as shown in Fig. 6, so that the opposite edges of the portions 4 will fit snugly against the adjacent sides of the package.

Each of the portions or parts 4 of the angular plate has but a single outer edge which is convexly arcuate, even and unbroken throughout its length, and its ends respectively join the ends of the outer edge of the other part 4 at the angle of joinder between said two parts 4.

The ridges 2 and groove 3 between them, in the completed seat, extend transversely to the angle of joinder, between and to the oppositely disposed convex edges of the portions 4, in the preferred form shown in the drawing.

In use, the strand seats 4 are applied to embrace meeting sides of the package, as shown in Fig. 1, and the binding strands, as wires, cords, ropes or cables 8 are disposed in the channels or grooves 3 of aligned seats 4.

The curvilinear, as convex, outer edges of each seat 4 prevent the seat from indenting or cutting into the package material, when the material is of relative soft texture, as pasteboard or paper sheets. The curvilinear edges also prevent the strand seats from cutting or bruising the fingers of the person who is applying the binding strands to the package.

As shown in Fig. 5, the channel or groove 3 extends across the angle of joinder between the two portions 4 of the seat, and the ridges 2 insure that the binding strand will not accidentally be displaced from the channel.

The strand seats are adapted to be nested in compact space for storage, when not in use.

Modifications of my invention, within the scope of the appended claim, may be made without departing from the spirit of my invention.

What I claim is:

A seat for a binding strand, which is to embrace two sides of a package, which sides meet at an angle to each other, comprising a plate consisting of two parts which meet at an angle of joinder approximately that between said two meeting sides, each of said two parts having a single outer edge convexly arcuate, even and unbroken throughout its length with its ends respectively joining, at said angle of joinder, the ends of the outer edge of the other of said two parts, said plate having in its outer side a strand receiving channel extending transversely across said angle of joinder.

RICHARD A. WALKER.
